UNITED STATES PATENT OFFICE.

GARROT E. STRUTHERS AND RAY M. STAMAN, OF WALNUT, IOWA.

CREAM SEPARATOR.

Application filed August 28, 1922. Serial No. 584,626.

To all whom it may concern:

Be it known that we, GARROT E. STRUTHERS and RAY M. STAMAN, each a citizen of the United States of America, and resident of Walnut, Pottawattamie County, Iowa, have invented a new and useful Cream Separator, of which the following is a specification.

An object of this invention is to provide improved means for driving the rotating elements of a cream separator.

A further object of this invention is to provide means for driving a cream separator by an electric motor and adjusting the revolutions per minute of the separator bowl relative to that of the motor.

A further object of this invention is to provide an improved interchangeable gear for use in transmitting power from an electric motor to the rotating elements of a cream separator.

A further object of this invention is to provide an improved step bearing for a cream separator motor.

Our invention consists in the construction, arrangement and combination of elements hereinafter set forth, pointed out in the claim and illustrated by the accompanying drawing, in which—

Figure 1 is an elevation, partly in section, showing our improvements applied as required for practical use. Figure 2 is a cross-section on the indicated line 2—2 of Figure 1. Figure 3 is a cross-section on the indicated line 3—3 of Figure 5. Figure 4 is a cross-section on the indicated line 4—4 of Figure 5. Figure 5 is an elevation, partly in section, of a gear assembly employed in the machine. Figures 3, 4 and 5 are on a scale enlarged relative to Figures 1 and 2. The lubricating system and elements are omitted from all views except Figure 1.

In the construction of the machine as illustrated, a frame or support for the motor and separator elements is shown conventionally and consists of a base 10, standards 11, 12, and a head 13, which may be suitably made, the head being adapted to contain a bowl 14 having any desired rotating and separating elements, milk-supplying devices and spouts not shown. An electric motor 15, shown conventionally, is mounted in the frame and is secured to the standards 11, 12 by supporting bands 16, 17, the armature shaft 18 of the motor being perpendicular to

the base and placed centrally of the frame. The armature shaft 18 has some freedom of movement longitudinally and the lower end thereof is reduced in diameter and is stepped on a ball 19 carried on a stud 20 in the base 10, a steadyng bearing 21 being carried by the base and embracing said armature shaft. A gear case 22, having a removable cover 23, of generally cylindrical form, is located between and supported by the standards 11, 12 above the motor 15 and the upper end portion of the armature shaft 18 is journaled in a central bearing or hole formed in the bottom of said gear case. A pinion 24 is removably and replaceably mounted on the upper end of the armature shaft 18 within the lower portion of the gear case 22 and is driven by said shaft. An internal gear 25 is mounted for rotation in the case 22 concentric with and spaced from the pinion 24; and pinions 26, in this instance three in number, are arranged in spaced relation in the case, are pivoted thereto and mesh with the pinion 24 and internal gear 25. The pinions 24 and 26 are of a width of face slightly less than one-half that of the internal gear 25. The pinions 26 preferably are pivoted to the bottom of the gear case 22 by arbors 27 seated interchangeably in holes 28, said holes being arranged in concentric rows to accommodate various diameters of pinions. A shaft 29 is journaled in a central bearing or hole formed in the cover 23 and the cover is adapted to be fixed to the case 22. A pinion 30 is fixed to the lower end of the shaft 29, within the gear case 22 and preferably is of greater diameter than the pinion 24. Pinions 31, in this instance three in number, are pivoted to the cover 23, are spaced apart and mesh with the pinion 30 and internal gear 25. The pinions 30 and 31 preferably are of a width of face slightly less than one-half that of the internal gear 25 and overlie and are spaced from the pinions 24 and 26 slightly, the shaft 29 being in alinement with and slightly spaced from the armature shaft 18 (dotted lines Figure 5). The pinions 31 preferably are pivoted to the cover 23 by arbors 32 seated interchangeably in holes 33, said holes being arranged in concentric rows to accommodate various diameters of pinions. The gear assembly can be modified in relation to the diameters of the pinions employed, to the end of changing the gear ratio and R. P. M. of the shaft 29 relative

to the armature shaft 18. The upper end portion of the shaft 29 is journaled in a bearing 34 in the head 13 and said shaft carries the rotatable elements of the cream separator within the bowl 14 and not shown. An oil fount, for lubricating oil, 35 is mounted above the horizontal plane of the bearing 34 and a feed pipe 36 leads from said fount to the interior of said bearing 10 and provides lubrication for the shaft 29 therein. An overflow pipe 37 leads from the interior of the bearing 34 to the interior of the steadyng bearing 21 and utilizes the overflow of oil from the upper bearing to 15 provide lubrication for the lower end of the armature shaft 18 and the step ball 19 in said lower bearing. An electric conductor 38, under control of a rheostat 39, provides current for operation of the motor.

20 We claim as our invention—

In a driving mechanism, a frame and a

shaft substantially centrally thereof, a motor mounted in said frame and having a shaft substantially in alinement with the first shaft, a gear case on said frame in 25 which said shafts are journaled, an internal gear rotatably mounted in said case, pinions fixed to the shafts concentrically of said internal gear and removable and replaceable relative to the respective shafts, said case 30 being formed with an assortment of arbor seats concentrically of said shafts and at different distances therefrom, and pinions of varying sizes having arbors adapted for interchangeable mounting in said seats and 35 adapted to connect the internal gear to the pinions on said shafts.

Signed at Walnut, in the county of Pottawattamie and State of Iowa, this 1st day of July, 1922.

GARROT E. STRUTHERS.
RAY M. STAMAN.
